Primary Examiner — Ian Simmons*Assistant Examiner* — Dana L Meyrow(74) *Attorney, Agent, or Firm* — Knobbe, Martens, Olson & Bear, LLP(57) **CLAIM**

The ornamental design for a plastic container, as shown and described.

DESCRIPTION

FIG. 1 is a top and side perspective view of a plastic container embodying my new design.

FIG. 2 is a side view of the plastic container of FIG. 1.

FIG. 3 is a 90 degree rotated side view from the side view of FIG. 2 of the plastic container of FIG. 1.

FIG. 4 is a top view of the plastic container of FIG. 1; and, FIG. 5 is a bottom view of the plastic container of FIG. 1. The portions of the plastic container shown in broken lines are for illustrative purposes only and form no part of the claimed design.
